UNITED STATES PATENT OFFICE.

CHARLES A. TATUM, OF NEW YORK, N. Y., ASSIGNOR TO WHITALL TATUM COMPANY, OF NEW YORK, N. Y., A CORPORATION OF NEW JERSEY.

ATOMIZER.

SPECIFICATION forming part of Letters Patent No. 728,328, dated May 19, 1903.

Application filed March 17, 1903. Serial No. 148,163. (No model.)

To all whom it may concern:

Be it known that I, CHARLES A. TATUM, a citizen of the United States, residing in the borough of Manhattan, city, county, and State of New York, have invented certain new and useful Improvements in Atomizers, of which the following is a specification.

My invention relates to that class of atomizers in which the atomizer proper when not in use may be placed within the bulb, so as to be protected thereby and to reduce the bulk of the apparatus.

The object of my present invention is to provide means for producing an air-tight joint between the bulb and the atomizer proper when the latter is in position for use and to prevent an accidental movement of the atomizer proper when it is within the bulb.

The invention will be fully described hereinafter and the features of novelty pointed out in the appended claims.

Reference is to be had to the accompanying drawings, which represent a typical form of my invention, and in which—

25 Figure 1 is an elevation with parts in section, showing the atomizer in position for use. Fig. 2 is a similar view with the atomizer proper within the bulb, and Fig. 3 is a plan of the device in the position shown in Fig. 2.

30 A is the bulb, which may be of any suitable construction. A substantially cylindrical bulb is shown, with its air-inlet indicated at A'. At the outlet I arrange a sleeve or thimble B, made of hard rubber or other suitable

35 material and provided with an internal screw-thread B'. A washer C is secured to the thimble, as by means of wire c, and the lower portion of this washer projects inwardly and has an annular edge or bead C'. This bead 40 is adapted to engage the outer surface of the atomizer proper, D, when the latter is within the bulb, as in Fig. 2, or the bottom of the atomizer proper when the latter is in the projected position, Fig. 1.

45 The construction of the atomizer proper may be varied considerably, although I prefer to use an atomizer the bottom of which is inclined, as shown at D'. I have shown a central tube E, through the medium of which 50 the air is blown from the bulb to the atomizer proper, and a liquid-conveying tube F, which

dips into the liquid contained in the atomizer and terminates adjacent to the outlet of the air-tube E. The outlet of the atomizer may be closed by a stopper G when it is desired to 55 invert the atomizer, as shown in Fig. 2.

The receptacle or body D of the atomizer proper is provided with a screw-thread D², adapted to fit the thread B' of the thimble B. When in position for use, the atomizer proper 60 is screwed into the thimble B, so as to project outwardly therefrom, as shown in Fig. 1, and the act of screwing in the atomizer proper presses the bottom thereof against the inner edge C' of the washer C. This is particularly the case when the atomizer has an inclined bottom D', as shown. In this manner an air-tight joint is obtained between the bottom of the atomizer and the washer C, and the entire amount of air expelled by the 65 compression of the bulb A is forced to pass into the air-conveying tube E.

It will of course be understood that the stopper G is removed when the atomizer is to be used.

75 When it is desired to place the atomizer within the bulb when not in use, the atomizer is first unscrewed from the thimble B and then inverted and introduced into the thimble in such inverted position. The diameter 80 of the smooth portion of the atomizer-body D is somewhat less than that of the threaded portion D², so that the main portion of the atomizer-body may be slid into the thimble B. The opening surrounded by the inner 85 edge C' of the washer C is slightly smaller than the cross-section of the main portion of the atomizer-body. Thus in sliding the atomizer-body through the washer into the position shown in Fig. 2 the washer will be 90 slightly distended and will hug the sides of the atomizer-body with sufficient friction to prevent any accidental displacement of the atomizer-body relatively to the bulb. I desire it to be understood that it is not necessary to screw the atomizer-body into the thimble in the position illustrated by Fig. 2, since the washer C efficiently holds the atomizer-body in position. The screw-threaded portion D² and the bottom D' project from the 95 thimble B, and thus afford a handle for conveniently withdrawing the atomizer-body.

from the thimble when it is desired to again assemble the parts in the position shown in Fig. 1.

Various modifications may be made without departing from the nature of my invention.

I claim—

1. The combination with an atomizer-bulb of a thimble arranged at the discharge end of the bulb, a perforated washer located at the inner portion of the thimble and an atomizer-body adapted for reversible connection with said thimble, the said washer being arranged to engage the bottom of the atomizer-body when the latter is in its extended or operative position, while the said washer engages and frictionally holds the side wall of the atomizer-body when the latter is inverted to extend through the thimble and the washer into the bulb.

2. The combination with an atomizer-bulb, of a reversible atomizer-body arranged to be received within the bulb or to be projected therefrom, and a perforated washer located at the discharge end of the bulb and arranged to clasp the side wall of the atomizer-body

when the latter is within the bulb, while when the atomizer-body extends outwardly from the bulb, the bottom of such body forms an air-tight joint with said washer.

3. The combination with an atomizer-bulb, of a thimble located at the outlet of said bulb and provided with an internal screw-thread, an atomizer-body, the main portion of which is of smaller diameter than the inner diameter of said thimble, said atomizer-body being provided with an inclined bottom, and adjacent thereto, with a screw-thread adapted to fit that of the thimble, and a perforated washer arranged to engage the inclined bottom of the atomizer-body when the latter is projected from the bulb, and to surround and frictionally engage the side wall of the atomizer-body when the latter is arranged within the bulb.

In testimony whereof I have hereunto set my hand in the presence of two subscribing witnesses.

CHARLES A. TATUM.
